(57) **CLAIM**

The ornamental design for a three-sided diamond whetstone with a basin, as shown and described.

DESCRIPTION

FIG. 1 is front elevational view thereof of a three-sided diamond whetstone with a basin showing my new design where the whetstone is placed in the basin;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is a perspective view thereof of a three-sided diamond whetstone with a basin showing my new design where the whetstone is separated from the basin.
